(57) **CLAIM**

We claim the ornamental design for a mobile computing device, as shown and described.

DESCRIPTION

FIG. 1 is a first perspective view of the first embodiment of a mobile computing device;

FIG. 2 is a second perspective view thereof;

FIG. 3 is a front side view thereof;

FIG. 4 is a rear side view thereof;

FIG. 5 is a first side view thereof;

FIG. 6 is a second side view thereof;

FIG. 7 is a top side view thereof;

FIG. 8 is a bottom side view thereof;

FIG. 9 is a first perspective view of the second embodiment of a mobile computing device;

FIG. 10 is a second perspective view thereof;

FIG. 11 is a front side view thereof;

FIG. 12 is a rear side view thereof;

FIG. 13 is a first side view thereof;

FIG. 14 is a second side view thereof;

FIG. 15 is a top side view thereof;

FIG. 16 is a bottom side view thereof;

FIG. 17 is a first perspective view of the third embodiment of a mobile computing device;

FIG. 18 is a second perspective view thereof;

FIG. 19 is a front side view thereof;

FIG. 20 is a rear side view thereof;

FIG. 21 is a first side view thereof;

FIG. 22 is a second side view thereof;

FIG. 23 is a top side view thereof;

FIG. 24 is a bottom side view thereof;

FIG. 25 is a first perspective view of the fourth embodiment of a mobile computing device;

FIG. 26 is a second perspective view thereof;

FIG. 27 is a front side view thereof;

FIG. 28 is a rear side view thereof;

FIG. 29 is a first side view thereof;

FIG. 30 is a second side view thereof;

FIG. 31 is a top side view thereof; and,

FIG. 32 is a bottom side view thereof.
